DESIGN FOR A CARPET OR SIMILAR ARTICLE

Charles Lehner, New York, N. Y., assignor to Bigelow Sanford Carpet Co. Inc., a corporation of Massachusetts

Application July 17, 1936, Serial No. 63,895

Term of patent 3½ years

To all whom it may concern:

Be it known that I, Charles Lehner, a citizen of the United States, residing at New York, in Queens County and State of New York, have invented a new, original, and ornamental Design for a Carpet or Similar Article, of which the following is a specification, reference being had to the accompanying drawing forming part thereof.

The figure of the drawing is a face view of a piece of carpet showing my design, the repeated design unit being contained within the area outlined by the dot and dash lines.

I claim:

The ornamental design for a carpet or similar article, as shown and described.

CHARLES LEHNER.
